UNITED STATES PATENT OFFICE.

DOMINICK W. SHARKEY, OF SYRACUSE, NEW YORK.

AEROPLANE.

1,315,044.

Specification of Letters Patent. Patented Sept. 2, 1919.

Application filed November 27, 1917. Serial No. 204,156.

To all whom it may concern:

Be it known that I, DOMINICK W. SHARKEY, a citizen of the United States, residing at Syracuse, in the county of Onondaga and State of New York, have invented a certain new and useful Improvement in Aeroplanes, of which the following is a specification, reference being had therein to the accompanying drawings, forming part thereof.

My invention relates to aeroplanes and has for its general object great strength, high speed, reliability, durability and other objects and advantages which will herein appear. My present invention relates more particularly to the propelling means, and the wing or plane construction disclosed herein forms the subject of my copending divisional application for Patent Serial No. 268,148, filed December 24, 1918.

My invention includes a propulsion tube forming the body of the aeroplane and provided with an annular adjustable air discharge opening together with means, such, for example, as a screw propeller, for producing an increased pressure of air within such tube, such tube being tapered toward its rear end. My invention also includes, in combination, wings forming planes secured to and extending laterally from the sides of such tube, a frame comprising a plurality of longitudinally extending members at the outside of the body-forming propulsion tube, and a plurality of rings tying such frame pieces or members together. My invention further includes features of construction and combinations of parts, as will appear from the following description.

I shall now describe the aeroplane embodying my invention illustrated in the accompanying drawings and shall thereafter point out my invention in claims.

Figure 1 is a top or plan view.

Fig. 2 is an enlarged partial longitudinal vertical section of the rear end of the aeroplane on a plane indicated by the line 2—2 of Fig. 1 as viewed from below.

Fig. 3 is a transverse section on planes indicated by the line 3—3 of Figs. 1 and 2 as viewed from the left, and drawn to a scale somewhat less enlarged than is Fig. 2.

Fig. 4 is a similar section on a plane indicated by the line 4—4 of Fig. 1 as viewed from the right.

Fig. 5 is a partial section similar to Fig. 4 but showing a wing as detached.

Fig. 6 is a front elevation on a reduced scale.

Fig. 7 is a side elevation as viewed from below in Fig. 1 and from the left in Fig. 6.

Fig. 8 is a somewhat enlarged central vertical longitudinal section with parts omitted.

Fig. 9 is a transverse section on a plane indicated by the line 9—9 of Fig. 8 as viewed from the right.

Fig. 10 is a similar view on the line 10—10 of Fig. 8.

Fig. 11 is a much enlarged vertical longitudinal section of one of the wings on a plane indicated by the line 11—11 of Fig. 1 as viewed from below.

Fig. 12 is a similar view on the line 12—12 of Fig. 1.

In the aeroplane embodying my invention illustrated in the accompanying drawings, a gradually rearwardly tapered sheet metal tube 1 forms a part of the body frame or fuselage of the machine. A sheet metal hood 2 of substantially semicircular cross-section and shown as slightly tapered in a forward direction extends forward from the upper part of the forward end of the tube 1, forming a forward continuation of the upper part of the tube 1, this semicircular hood 2 also forming a part of the wing-supporting framework or fuselage of the machine. The framework or fuselage also includes longitudinal frame pieces 3, shown as four in number, equidistantly transversely circumferentially spaced and tied together at intervals by means of transversely arranged rings 4, these frame parts being of any suitable metal or alloy.

Wings or planes, forming more particularly the subject of my above mentioned divisional application, project laterally in opposite directions from the fuselage and are detachably secured to the sides of the body-forming rearwardly tapered tube 1 and to the lower edges of the forwardly extended hood 2. These wings have gradually outwardly tapered V-shaped sheet metal ribs 5 extending laterally in parallel relation at right angles to the longitudinal axis of the machine, and shown as seven in number for each wing, and these wing-ribs 5 are all of similar construction, but vary as to their length and cross-section. The lower air-engaging wing surface of the wing is formed by a lower metallic sheet 6, which is firmly secured by means of rivets 7 (Figs. 11 and 12) to lateral flanges

8 formed on the wing-ribs 5. At their inner or larger ends the wing-ribs 5 are provided with end flanges 9 which conform to and are firmly secured, by means of rivets 10, to a curved end plate 11. These end plates 11 are curved to conform to the outer surfaces of and are adapted to be detachably secured in place upon the tube 1 and hood 2 of the fuselage or framework of the machine, and are shown as thus secured in place by means of two sets of upper short bolts 12 and by a single set of lower long bolts or tie rods 13 which extend transversely from side to side through the lower edges of the hood 2 and transversely across the tube 1 just below the axis or center line thereof. Simply by removing the outwardly exposed nuts from these bolts 12 and rods 13, the wings may be detached from the body or fuselage, thus providing for convenient transportation and for the easy making of repairs. The flat sheet metal plate 6 forming the lower wing surfaces is provided between the wing-ribs 5 with apertures 14 of comparatively small diameter, these holes 14 permitting the passage of small quantities of air from the lower to the upper sides of the wings between the ribs 5, so as thereby to prevent the forming of objectionable eddy currents in the air above the wings by the wing-ribs 5. It will be noted that the wings and entire body structure or fuselage are formed entirely of metal, so that their construction is such as to provide great strength combined with lightness.

In carrying out my present invention, the body-forming tube 1 of the fuselage is also a propulsion tube for driving the aeroplane forward, and for accomplishing this result means are provided for compressing air in the tube 1, which may enter at the forward open end of the tube, and which, by reason of such compression, will be forcibly expelled from the rear contracted end of this tube 1. In the construction illustrated in the drawings, a screw propeller 15 is located within the tapered tube 1 near its forward flaring end and has a large number of blades, shown as six, for thereby effectively compressing the air within the tube 1 at the rear of the propeller 15, which is of a diameter substantially filling the tube 1. The propeller 15 is fixed upon a propeller shaft 16, and the propeller shaft 16 is shown as extending axially through the tube 1 from end to end thereof, at its rear end being journaled in a bearing 17 carried by a strut 18 at the rear end of the tapered propulsion tube 1, and at the flaring forward end of this tube 1, the propeller shaft 16 is journaled in a bearing 19 carried by a strut 20. From the bearing 19 the propeller shaft 16 extends forward to an engine 21, which may be of a usual or of any suitable construction, and is shown as lo-

cated at the forward end of the body framework or fuselage forwardly of the forward edge of the wings. The engine 21 drives the propeller 15, and air entering the forward flaring or enlarged open end of the 70 propulsion tube 1 is compressed within this tube by the propeller 15, and by reason of this compression the air is ejected rearwardly through the reduced rear end of the tube 1, and by its reaction drives the aero- 75 plane in a forward direction.

In order to obtain a maximum propulsive effect, a restricted air discharge opening of annular form is provided at the rear end of the tube 1. A forwardly tapered or rearwardly flaring cone is located centrally of the rear end of the rearwardly tapered tube 1 for producing a restricted air outlet of annular form, whereby air under compression may accumulate within the rearwardly 80 tapered propulsion tube 1 at the rear of the propeller 15 and by reason of its compression will be discharged at high velocity through such restricted annular outlet. Means are provided for adjusting the area of this annular air outlet, and in the construction illustrated in the drawings, the cone is made adjustable for radial expansion or contraction of its periphery. For effecting such adjustment the cone is shown as comprising 85 a plurality of tapered curved overlapping sheet metal plates 22, which at their forward ends are hinged or pivoted to a central front member or collar 23, which is slidable upon the propeller shaft 16, which is shown 90 as of reduced diameter rearward from the propeller 15. Each of the curved tapered sheets 22 is pivotally connected at a median point thereof by means of a link 24 with a stationary central member or spider 95 25 shown as formed upon the forward end of the rear bearing 17 for the propeller shaft 16.

It will be noted that the links 24 are inclined toward the rear as they approach the 100 spider 25, so that sliding movement of the collar 23 upon the propeller shaft 16 will cause the overlapping cone plates 22 to open or to close substantially like an umbrella, the arrangement being such that 105 movement of the sliding collar 23 to the rear will cause an opening movement of the cone, and forward movement of the collar 23 will cause a closing movement of the cone. In the construction illustrated in the 110 drawings, manually operated means are shown for effecting the opening or closing movement of the cone-forming plates 22. In this construction such manually operated means comprise a bell-crank lever 115 26 pivoted on a bearing 27 carried by the rear strut 18 and having an upstanding arm which is pivotally connected by means of a link 28 with one of the links 24, and this bell-crank lever 26 has a rear arm which 120 125 130

is connected by an operating rod or link 29 with the longer rearwardly extending arm of a double bell-crank or T-shaped lever 30, which is pivoted upon a bearing bracket 31 shown as projecting from the 5 rearmost ring 4 of the fuselage or framework of the machine. The two remaining arms of the T-shaped or double bell-crank levers 30 are connected by means of two operating wires 32 with a similar double bell-crank or T-shaped lever 33 pivoted upon a bearing bracket 34 shown as mounted upon the top of the forwardly extending sheet metal hood 2. The remaining and 10 forwardly extending longer lever arm of the double bell-crank lever 33 has a handle rod 35 pivoted thereto and extending downward through an opening in the hood 2 to a convenient position for operation by the 15 aviator. This rod or bar 35 is shown as notched to provide ratchet teeth for engaging the edge of the hood 2 at the opening, and these teeth are adapted to be held in engagement by means of a retractile spring 20 36. It will now be evident that by moving the handle rod 35 up or down to different positions of adjustment, the overlapping cone-forming plates 22 will be opened or closed, thereby correspondingly adjusting 25 the peripheral dimension or diameter of the cone which they form and correspondingly varying the area of the annular air outlet between such cone and the reduced rear end of the rearwardly tapered propulsion tube 30 36. 1. In the drawings this cone is shown as adjusted to substantially maximum diameter for correspondingly restricting the annular air outlet to a minimum area which may be enlarged by reducing the diameter of the adjustable cone, as will be readily understood and as is clear from the drawings.

It will be noted that the air has free entry to the open larger forward end of the 45 propulsion tube 1, particularly to the lower half of such forward end, it being noted that there are no nearby obstructions adjacent to the forward open end of this tube 1. The propeller 15 compresses the entering 50 air within the tapered tube 1 and the escape of this compressed air rearward through the tapered restricted annular outlet drives the aeroplane in the forward direction. The adjustment of the area of this 55 air discharge outlet, effected by means of the peripherally adjustable cone as hereinbefore described, provides for obtaining a maximum propulsive effect under different conditions, such for example, as at different 60 speeds of forward travel and also for the different conditions encountered at various altitudes, the rarefied air at high altitudes requiring more compression. In the construction illustrated in the drawings, an 65 aviator's seat 37 is shown in Fig. 1 as lo-

cated beneath the hood 2, such machine being supposed to be of sufficient size to permit of the aviator sitting within and beneath this hood 2 with ample head room therein. However, in a smaller machine, a suitable 70 opening could be provided in this hood 2 above which the aviator's head could then project, as will be readily understood and similarly to usual practice in this respect in other aeroplanes of a substantially different construction in other respects. 75

Other parts of the aeroplane, some of which appear in the accompanying drawings, and not hereinbefore particularly described, may be of a usual or of any suitable construction. It will be noted that there are provided a vertical rudder 38, a horizontal rudder 39, a control wheel 40, and a landing gear 41, all substantially as usual in aeroplane construction. It is further to be noted that lateral balancing control may be effected in substantially a usual way by warping the outer ends or tips of the wings, which are sufficiently flexible for this purpose, and this warping of the wings 90 to obtain the lateral balancing control may be effected in substantially a usual way by means of usual guys 42, appearing in Fig. 6. These guys 42 also strengthen the wings in a substantially usual way. 95

It is obvious that various modifications may be made in the construction shown in the drawings and above particularly described within the principle and scope of my invention. 100

I claim:

1. An aeroplane having, in combination, a longitudinally extending propulsion tube tapered at its rear end to form a reduced air discharge outlet, a rearwardly flaring cone 105 disposed in the discharge end of said tube so as to provide a further reduced annular air discharge outlet, and means for compressing the air within said tube at the front of said cone. 110

2. The invention claimed in claim 1 in which said means is a screw propeller located within said tube near the open forward end thereof.

3. The invention claimed in claim 1 in 115 which means are provided for adjusting the size or area of the annular air discharge outlet between said cone and the inner wall of said tube.

4. The invention claimed in claim 1 in 120 which means are provided for adjusting said cone so as to vary the air discharging capacity of the annular air outlet within said tube around the periphery of said cone.

5. The invention claimed in claim 4 in 125 which said cone is adapted for radial expansion or contraction of its periphery.

6. The invention claimed in claim 1 in which said propulsion tube is a body-forming tube, in combination with wings form- 130

ing planes attached to the sides of and projecting laterally from said tube.

7. The invention claimed in claim 6 in combination with a plurality of frame pieces 5 extending longitudinally at the outside of said body-forming propulsion tube, and a plurality of rings tying together said frame pieces.

8. An aeroplane having, in combination, 10 a longitudinally extending body-forming propulsion tube, means for impelling air sternward through said tube, a transversely curved hood extending forward from the upper part of the forward end of said tube, 15 and laterally projecting wings forming planes secured to the lower edges of said hood and to the sides of said tube.

9. The invention claimed in claim 8 in combination with tie rods extending trans- 20 versely from side to side and connecting together the lower edges of said hood.

10. The invention claimed in claim 8 in combination with tie rods connecting together the lower edges of said hood and 25 other similar tie rods extending transversely across said body-forming propulsion tube.

11. The invention claimed in claim 1 in which said cone comprises a plurality of tapered transversely curved peripherally 30 overlapping plates, and means for varying the extent of overlap of the plates for thereby effecting radial and peripheral expansion or contraction of the cone.

12. An aeroplane having, in combination, a longitudinally extending propulsion tube, 35 a rearwardly flaring cone disposed in the rear end of said tube to provide an annular air discharge outlet, and means for compressing the air within said tube at the front of said cone; said cone comprising a 40 plurality of tapered transversely curved peripherally overlapping plates, a central front member to which the forward reduced ends of said plates are pivoted for radial swinging movement, a central rear member, 45 links pivotally connecting said plates to said rear central member, and means for varying the distance between said front and rear central members for thereby varying the diameter of the larger end of the cone. 50

13. The invention claimed in claim 12 in which said air compressing means is a screw propeller, in combination with a propeller shaft upon which said cone is mounted.

14. The invention claimed in claim 12 in 55 which said forward central member of the cone is movable and said rear central member is stationary.

15. The invention claimed in claim 13 in which said rear central member of the cone 60 is stationary and said forward central member is slideable along the propeller shaft for adjusting the diameter of the cone.

In testimony whereof I have affixed my signature to this specification.

DOMINICK W. SHARKEY.
